UNITED STATES PATENT OFFICE.

THOMAS P. DUNNE AND PAUL RATH, OF NEW YORK, N. Y.

SASH-CORD FASTENER.

SPECIFICATION forming part of Letters Patent No. 247,027, dated September 13, 1881.

Application filed July 7, 1881. (No model.)

To all whom it may concern:

Be it known that we, THOMAS P. DUNNE and PAUL RATH, both of the city, county, and State of New York, have invented an Improved Sash-Cord Fastener, of which the following is a specification.

The object of our invention is to provide a new and improved device for fastening a sash cord or chain to the sash in such a manner that it can be attached or detached very rapidly and conveniently without removing the parting-strip or stop-bead.

The invention consists in a flanged and ribbed sleeve, through which the lower end of the sash-cord is passed, the strands of the cord being separated and turned down on the outside of these ribs, and held thereon by a screw-cap, which is passed over these ribs and is screwed into the lower end of an angular inclined aperture passing from the outer edge to the inner surface of the side rail of the sash, through which angular aperture the cord passes. If a sash-chain is to be held, the short sleeve is provided at its inner end with two prongs, between which the chain is passed.

In the accompanying drawings, Figure 1 is a longitudinal sectional elevation of an end rail of a sash provided with our improved device for fastening or holding a sash-chain to the sash. Fig. 2 is a diagonal cross-sectional view of the same on line *x x*, Fig. 1. Fig. 3 is a longitudinal sectional elevation of an end rail of a sash provided with our improved device for fastening or holding a sash-cord to the sash. Fig. 4 is a diagonal cross-sectional view of the same on the line *y y*, Fig. 3. Fig. 5 is a side elevation of the screw-cap. Fig. 6 is a side elevation of the short sleeve provided with the prongs.

Similar letters of reference indicate corresponding parts.

A hole, A, is bored in the side rail, B, of a sash from the outer edge of the same diagonally downward, and a hole, C, is bored into the inner surface of the end rail, D, in such a manner that it meets the lower end of the diagonal hole A. The lower end of the sash-cord D is passed downward through the holes A and C and through a short sleeve, E, with

a flange, F, at the inner end, and external ribs G projecting at right angles thereto. The strands H of the cord D are separated, and are bent and turned down on the ribs G in such a manner that they are between the ribs G. A cap, J, with a threaded flange, K, and a slot, L, is passed over the ribs G, and the ends of the strands H are clamped between the said ribs and the cap J, and are thus fastened to the cylinder. A sharp-edged instrument is passed into the slot L, and the cap is screwed into the end of the hole C in such a manner that the surface of this cap will be flush with the inner surface of the side rail, B. The cord D passes through the groove M in the ordinary manner. Before the lower end of the cord is secured to the sleeve E the cord is cut to the proper length. If a sash-chain, N, is used, the sleeve E must be provided with two inwardly-projecting prongs, O. The chain N is passed through the apertures A and C, and the sleeve E is passed into the hole C in such a manner that the end link, P, of the chain N passes in between the prongs O in such a manner that a joint part or enlarged part of the link P is at each end of the prongs O, thus holding the chain very firmly. The cap J is passed over the sleeve E and screwed into the end of the aperture C in the manner described.

Having thus described our invention, we claim as new and desire to secure by Letters Patent—

1. In a sash-cord fastening, the combination, with a sash, recessed as shown and described, and with the sash-cord, of the sleeve E and the screw-cap K, substantially as and for the purpose set forth.

2. In a sash, the combination, with the sash-cord D, of the short sleeve E, provided with ribs G, and a flange, F, and of the cap J, provided with a threaded flange, K, substantially as herein shown and described, and for the purpose set forth.

THOS. P. DUNNE.
PAUL RATH.
